UNITED STATES PATENT OFFICE

1,996,931

WINDOW GRATING

Bernard A. McGuinness, Belmont, Mass.

Application September 10, 1934, Serial No. 743,364

4 Claims. (Cl. 20—71)

This invention relates to window gratings for use in preventing would-be intruders from entering through windows or other openings, and more particularly to a grating of the type in which the bars may be readily moved to and from the window barring position.

It has been proposed heretofore to provide gratings in which the bars may be moved from a window barring position to a stored position at a side or end of the window and these grating bars are frequently connected by pivoted links adapted to limit the distance between the bars and to maintain them in substantially parallel relation to each other as they are moved to and from the window barring position. These folding links, however, occupy considerable space when the bars are moved to their inactive or stored position adjacent the window.

The present invention therefore pertains to a window grating provided with bars supported for movement to and from the window barring position and having co-operating rack and pinion means associated with the bars and operable to retain the bars in parallel relation with each other as they are moved along the bar supporting means.

A more specific form of the invention resides in a series of separate grating bars each provided with pinions or small gears at their opposite ends and in guide rails for supporting these bars for movement to and from the window barring position, each rail has associated therewith a rack which co-operates with the pinions of the bars to maintain the bars in parallel relation to each other as they are moved along the guide rails. A further feature of the invention resides in locking means for locking the bars along the rails in spaced relation to each other.

Other features of the invention and novel combination of parts in addition to the above will be hereinafter described in connection with the accompanying drawing which illustrates one good, practical form of the invention.

In the drawing:

Fig. 1 is a front elevation of a window provided with a grating of the present invention and shows the bars in the window barring position.

Fig. 2 is a similar view showing the bars in the inactive or stored position at one side of the window.

Fig. 3 is a vertical sectional view through the window of Fig. 1.

Fig. 4, on a larger scale, is a transverse sectional view through the upper and lower bar supporting rails.

Fig. 5 is a top plan view of the lower guide rail, the grating bars being shown in section.

Fig. 6 is a plan view of a strip for locking the bars in the window barring position; and

Fig. 7 is a sectional view taken on the line 7—7 of Fig. 4.

The protecting grating of the present invention may be used in connection with windows of the ordinary home or other buildings, and while this protecting grating has been shown and described herein in connection with windows it is to be understood that it may be employed in connection with doors or other openings where its protection is desired.

The window frame shown which may be of the usual construction has the sides 10, top portion 11, and sill or lower portion 12, and in this window frame are slidably mounted the upper sash 13 and lower sash 14.

The window grating of the present invention is formed of the grating bars 15 that are supported for movement from the window barring position of Fig. 1 to their inactive or stored position of Fig. 2. These bars in the construction shown are supported in a vertical position and extend throughout the length of the window from the lower portion of the frame 12 to the upper portion 11 and the bars are supported at their upper end by the guide rail 16 and at their lower end by the guide rail 17. The upper guide rail is conveniently secured by screws or the like to the under face of the frame portion 11, and the lower rail 17 may be similarly secured by screws 18 to the upper face of the sill board 121.

An important feature of the present invention, as above stated, is to provide means for maintaining the bars 15 in parallel relation to each other as they are moved along the guide rails 16 and 17 so that one bar cannot be shifted to an inclined position in the window frame and cause its ends to be disengaged from the guide rails.

In the embodiment of the invention shown this object of the invention is secured by providing the upper guide rail 16 with a rack 19 and the lower guide rail 17 with a similar rack 20 and by providing a pinion or small gear 21 at the upper and lower end of each grating bar 15, the arrangement being such that these pinions are held in mesh with their respective racks as the bars 15 are moved to and from the window barring position.

In the construction shown the pinions 21 are formed by cutting teeth in the end portions of the bars 15, as will be apparent from the drawing. These teeth 21 are held in engagement with

the upper rack 19 by the guide strip 22 which is preferably bent so that it has the shape in cross section best shown in Fig. 4, and the upper horizontally extending portion of the strip 22 is rigidly secured by screws 23, or other means, to the rack 19, while the downwardly extending portion of this strip is provided adjacent its lower edge with an inwardly extending rib 24 which bears upon the smooth cylindrical surface of the rod 15 below the teeth of the pinion 21. As a result of this construction the portion 24 provides a straight guiding edge that co-operates with the rounded portion of the bar to guide the bar along the rail 16 and hold its teeth properly engaged with the rack 19.

It is important that means be provided for locking the bars 15 spaced along the guide rails 16 and 17 in the window barring position, and this is accomplished in the construction shown by providing the lower guide rail 17 with the bar locking strip 25 best shown in Fig. 6.

The lower guide rail 17 is therefore provided with a guiding strip 26 which is conveniently given the hollow channeled construction best shown in Fig. 4, the channel portion of which serves to house and slidably support the locking strip 25. The channel strip 26 has a horizontal portion that extends under the rack 20 and is rigidly secured thereto by screws similar to the screws 23 above mentioned and an upwardly extending portion of the strip 26 is provided with the upper horizontally extending portion 27, the edge of which engages the bars 15 above the teeth of the pinion 21 and serves to guide the bars and hold the teeth at their lower end in mesh with the rack 20.

The locking strip 25 is mounted within the channeled portion of the strip 26 for sliding movement into and out of locking engagement with the bars 15, and in the construction shown the grating bars are locked in their window barring position by providing in one edge of the strip 25 the bar receiving notches or arcuate portions 28 adapted to partially embrace each lower pinion 21 as will be apparent from Fig. 7. The movement of the strip 25 into and out of locking engagement with the bars 15 is secured in the construction shown by providing the strip 25 with two or more inclined slots 29 formed therein and adapted to receive the guide pins 30 which extend transversely through the channeled portion of the guide strip 26 and are rigidly secured in this channel strip to guide the locking strip 25 along a diagonal path as it is moved from its inactive position in which it is shown in dotted lines in Fig. 5, to its bar locking position, in which it is shown in Fig. 7.

The strip 25 may be manually shifted along the diagonal path just mentioned by the operating pin 31 which extends through a diagonal slot 32 formed in the upper portion 27 of the channel strip.

It is important that means be provided for holding the locking strip 25 in its bar locking position so that this strip cannot be shifted by an unauthorized person to release the grating bars. This is accomplished in the construction shown by providing at one end of the strip 25 the latch engaging projection 33 having a shoulde

ered portion adapted to be engaged by the spring operated latch 34 of the lock 35, which lock may be housed in the channeled portion of the strip 26 and so positioned therein that the spring operated latch 34 will automatically move into locking engagement with the projection 33 as

the strip 25 is moved in an inclined direction to the right, viewing Fig. 5, to the bar locking position.

When it is desired to release the bars 15 it is merely necessary to insert a key in the lock 35 and swing the latch 34 out of engagement with the extension 33 whereupon the strip 25 will be released and may be moved manually to its bar releasing position of Fig. 5. Upon the upper face of the locking strip 25 is preferably provided a spacing member 36 adapted to fill the space between the upper face of the strip 25 and lower inner face of the channeled portion 27 to thereby hold the locking strip 25 against vertical play within its housing.

The upper guide rail 16 and lower guide rail 17 preferably extend throughout the entire width of the window so that the pinions of the bars 15 will be held in engagement with the racks 19 and 20 throughout the movement of these bars from the stored position of Fig. 2 to the window barring position of Fig. 1.

The upper guide strip 22 and lower guide strip 26 may conveniently be formed of sheet metal which is rigidly secured to the racks 19 and 20, respectively, as above pointed out. It will therefore be seen that these guide rails are comparatively inexpensive to construct and may be easily installed in windows of various widths by simply cutting each rail to the desired length and securing these rails in place upon the window frame as above described. It will also be seen that the rack and pinion construction herein described forms an extremely simple means for maintaining the grating bars 15 in parallel relation to each other throughout their movement along the guide rails and that the means herein described for locking the lower ends of the bars 15 in the guide rail 17 serves also to lock the upper ends of the bars 15 within the guide rail 16 due to the fact that the upper ends of these bars cannot be moved along the guide rail when the bars are prevented from turning by the locking means associated with the guide rail 17. The lower guide rail 27 may be provided with the arrows or other similar marks 37 upon its upper face to indicate the position the bars 15 should occupy when these bars have been moved to the window barring position and are ready to be locked in this position by the locking strip 25, and the ends of the channeled rails 16 and 17 may be closed by the end plates 38.

I claim:

1. In combination with a window, a grating therefor comprising vertical grating bars, guide rails at the opposite side of said bars for supporting the bars in the window barring position and for movement along the rails to a position adjacent the sides of the window, pinions at the opposite ends of the bars, a rack associated with each rail and having the pinions meshed therewith to maintain the bars in parallel relation to each other as they move along the rails, and a locking strip associated with one rack and movable into and out of locking engagement with the bars to lock them to this rack and effect a locking action between the other ends of these bars and their rack whereby all grating bars may be locked and released at both ends without moving the bars.

2. In combination with a window, a grating therefor comprising vertical grating bars, guide rails at the opposite ends of said bars for supporting the bars in the window barring position and for movement along the rails to a position

adjacent the sides of the window, pinions at the opposite ends of the bars, a rack associated with each rail and having the pinions meshed therewith to maintain the bars in parallel relation to each other as they move along the rails, and locking means associated with one rack and movable into and out of locking engagement with the bars adjacent this rack to lock the bars to this rack and effect a locking action between the other ends of these bars and their rack whereby all grating bars may be locked and released at both ends without moving the bars.

3. In combination with a window, a grating therefor comprising vertical grating bars, guide rails at the opposite ends of said bars for supporting the bars in the window barring position and for movement along the rails to a position adjacent the sides of the window, pinions at the opposite end of the bars, a rack associated with each rail and having the pinions held in engagement therewith to maintain the bars in parallel relation to each other as they are moved along

the rail, and a locking strip movable into and out of locking engagement with said bars to prevent the pinions at the opposite ends of the bars from traveling along their respective racks whereby all grating bars can be locked and released at both ends without moving the bars.

4. In combination with a window, a grating therefor comprising vertical grating bars, guide rails at the opposite ends of said bars for supporting the bars in the window barring position and for movement along the rails to a position adjacent the sides of the window, pinions at the opposite ends of the bars, a rack associated with each rail, a bar guiding strip upon each rail and positioned to engage a rounded portion of the bars to hold the pinions in mesh with the racks to maintain the bars in parallel relation with each other, and a locking strip associated with one rack and movable into and out of locking engagement with the bars to lock them in place through the racks and pinions.

BERNARD A. McGUINNESS.
